United States Patent Office

Des. 229,473

Patented Dec. 4, 1973

229,473

NEWSPAPER COLLECTION CONTAINER

Charles T. Henry, 7114 Kingsbury Blvd.,
University City, Mo. 63130

Filed July 18, 1972, Ser. No. 272,764

Term of patent 14 years

Int. Cl. D7—07

U.S. Cl. D7—191

FIG. 1.

FIG. 2.

FIG. 3.

FIG. 4.

FIG. 1 is a front perspective view of a newspaper collection container showing my new design;

FIG. 2 is a top plan view;

FIG. 3 is a front elevational view; and

FIG. 4 is a side perspective view.

The bottom is smooth and planar and the end walls are mirror images of one another.

I claim:

The ornamental design for a newspaper collection container, as shown and described.
